UNITED STATES PATENT OFFICE

169,721

PHOTOGRAPHIC LIGHT METER

Hans A. Bakke, Swampscott, Mass., assignor to
General Electric Company, a corporation of
New York

Application September 26, 1952, Serial No. 21,608

Term of patent 14 years

(Cl. D61—1)

To all whom it may concern:

Be it known that I, Hans A Bakke, a citizen of the United States, residing at Swampscott, in the county of Essex, Commonwealth of Massachusetts, have invented a new, original, and ornamental Design for a Photographic Light Meter, of which the following is a specification, reference being had to the accompanying drawing, forming a part thereof, in which

Fig. 1 is a front view of a photographic light meter showing my new design;

Fig. 2 is a back view of the same meter;

Fig. 3 is an end view of the same meter; and

Fig. 4 is a side view of the same meter.

I claim:

The ornamental design for a photographic light meter, as shown.

HANS A. BAKKE.
